Patented June 23, 1925.

UNITED STATES PATENT OFFICE.

ARTHUR C. HOPKINS, OF NILES, MICHIGAN, ASSIGNOR TO NATIONAL STANDARD COMPANY, OF NILES, MICHIGAN.

CRANK FOR LIFTING JACKS.

Application filed August 16, 1924. Serial No. 732,580.

To all whom it may concern:

Be it known that I, ARTHUR C. HOPKINS, a citizen of the United States, residing at Niles, county of Berrien, State of Michigan, 5 have invented certain new and useful Improvements in Cranks for Lifting Jacks, of which the following is a specification.

This invention relates to improvements in cranks for lifting jacks.

10 The main object of this invention is to provide an improved crank for lifting jacks which may be collapsed into a comparatively compact form and one which, when extended for use is quite rigid and does not 15 collapse.

Objects pertaining to details and economies of my invention will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing forming a part of this application, in which:

Fig. I is a side view of a lifting jack equipped with my improved crank.

Fig. II is a plan view of the crank collapsed.

Fig. III is a transverse section on a line corresponding to line 3—3 of Fig. II.

Fig. IV is an enlarged transverse section on a line corresponding to line 4—4 of 35 Fig. II.

In the drawing the sectional views are taken looking in the direction of the little arrows at the ends of the section lines and similar numerals of reference indicate 40 similar parts in all of the views.

Referring to the drawing, the jack designated generally by the numeral 1 is of the type illustrated in my application for patent filed June 28, 1924, Serial No. 722,938.

45 This jack is provided with a driving gear 2 having a socket 3 adapted to receive the shank.

My improved crank comprises an inner section 4 of rectangular cross section. This section is provided with stops 5 and 6 adjacent its ends, the stop 6 being spaced from the inner end of the section 4 providing a tang portion 7 adapted to enter the socket 3.

55 The outer section 8 is of circular cross section and has a slide 9 rigidly secured

thereto by the rivets 10 to slidely embrace the section 4 between the stops 5 and 6 so that the sections may be telescoped or collapsed together as shown in Fig. II or extended as shown in Fig. I. The outer 60 section 8 has an offset 11 therein providing a crank, the outer arm 12 of this offset being extended transversely of the shaft sections of the crank and terminating in a grip or crank 13 disposed in a plane 65 parallel to the longitudinal plane of the shaft, thus providing two cranks or grips.

To permit the complete collapsing of the sections the part 12 is bent as shown in Fig. III so that it may telescope or slide 70 over the section 4. This permits of the extension of the crank to its full length as shown in Fig. I, or the partial extension thereof for use, as may be desired. When extended for use the crank cannot collapse 75 as is likely to occur with cranks having hinged joints; at the same time, the structure is readily extended or collapsed, and, when collapsed is quite compact.

Having thus described my invention what 80 I claim as new and desire to secure by Letters Patent is:

1. A crank of the class described comprising an inner shaft section of rectangular cross section provided with stop lugs adjacent its ends, an outer shaft section of circular cross section disposed at the side of said inner section, and a slide secured to the inner end of said outer section to slidably embrace said inner sections between said stops, the outer end of said outer section having an offset therein providing a crank, the outer arm of said offset being extended beyond the plane of the said shaft and turned outwardly to provide a second crank, the said arm being bent longitudinally permitting it to slide over the said inner section when the outer section is telescoped therewith.

2. A crank of the class described comprising an inner shaft section of rectangular cross section provided with stop lugs adjacent its ends, an outer shaft section of circular cross section disposed at the side of said inner section, and a slide secured to the inner end of said outer section to slidably embrace said inner section between said stops, the outer end of said outer section having an offset therein providing a crank, the outer arm of said offset being

extended beyond the plane of the said shaft and turned outwardly to provide a second crank.

3. A crank of the class described comprising an inner shaft section, and an outer shaft section disposed at the side of said inner section and slidably secured thereto, the outer end of said outer section having an offset therein providing a crank, the outer ¹⁵ arm of said offset being extended beyond

the plane of the said shaft and turned outwardly to provide a second crank, the said outer arm being bent longitudinally to permit it to slide over the said inner section when the outer section is telescoped therewith.

In witness whereof I have hereunto set my hand.

ARTHUR C. HOPKINS.
